UNITED STATES PATENT OFFICE.

PETER ANDERSEN, OF RACINE, WISCONSIN.

HAMMER.

Application filed March 9, 1927. Serial No. 173,898.

This invention relates to improvements in hammers and more particularly to a hammer adapted primarily for use by bricklayers, carpenters and like tradesmen. One object is to 5 provide a hammer that is of simple construction, cheap to manufacture and efficient in use.

With the foregoing and other objects in view the invention consists in the combination and arrangement of parts to be hereinafter 10 fully described, particularly pointed out in the appended claim and illustrated in the accompanying drawing which forms a part of this application and in which—

Fig. 1 is an end view of the hammer.
15 Fig. 2 is a sectional view in side elevation.
Fig. 3 is a cross section taken on line 3—3 of Fig. 1.

Like reference characters denote corresponding parts throughout the several views.
20 The present invention provides a hammer having a head comprising a blade and heel and formed with a handle-receiving eye or perforation that is wider at one end than at the other to facilitate retention of the handle,
25 the blade having a cutting edge disposed at right angles to the handle axis and formed with a marginal recess to permit the use of the tool as a nail puller.

The reference numeral 1 denotes the head 30 formed with the neck 2, heel 3 and blade 4. The head and neck are formed with the eye or perforation 5 to receive the handle 6, said eye increasing slightly in its diameter as it recedes from the neck so that the handle may 35 be introduced therein and then by the introduction of the screws 7 to spread and wedge it at its end to effectually prevent its withdrawal.

The handle is disposed at right angles to the edge of the blade and a notch or recess 40 8 cut in one edge of the head is disposed at right angles to the blade, the sides of the recess being straight and parallel. With the hammer resting upon its head the recess 8 is caused to receive the body of an upstanding 45 nail to be removed, as from a scaffold or the like, and the hammer oscillated upon its heel to extract the nail. The lateral edge of the head wherein the recess 8 is formed is provided with the opposed short recesses 9, 10 50 55 that open into the recess 8 so that a nail or tack that does not extend above the material as great a distance as the length of the recess 8 may be extracted, the head of the nail or tack being received in the short recesses while the nail or tack body lies in the recess 8 and when the hammer is moved to raise the blade, upon the heel as a pivot, the nail or tack is raised out by its head.

What is claimed is:—

In a hammer, a head terminating at one end in a blade, said head being formed with a transverse recess along one of its lateral edges in a position at right angles to said blade, said recess extending a substantial distance inwardly from said lateral edge and intersecting the two broad faces of the head, the sides of said recess being parallel, said head being formed further with opposed longitudinally extending recesses opening into said transverse recess at right angles thereto, substantially as and for the purpose set forth.

In testimony that I claim the foregoing as my own I have hereto affixed my signature.

PETER ANDERSEN.
